Primary Examiner — T. Chase Nelson*Assistant Examiner* — Mark Cavanna(74) *Attorney, Agent, or Firm* — Hahn & Voight PLLC;
Roger C. Hahn(57) **CLAIM**

I claim the ornamental design for an electrode pad, as shown and described.

DESCRIPTION

FIG. 1 is a perspective view of an electrode pad with the tab portions shown flat, showing my new design;

FIG. 2 is a top view of the electrode pad referenced in FIG. 1;

FIG. 3 is a bottom view of the electrode pad referenced in FIG. 1;

FIG. 4 is a left side view of the electrode pad referenced in FIG. 1;

FIG. 5 is a right side view of the electrode pad referenced in FIG. 1;

FIG. 6 is a rear view of the electrode pad referenced in FIG. 1;

FIG. 7 is a front view of the electrode pad referenced in FIG. 1;

FIG. 8 is an exploded view of the central section of the electrode pad referenced in FIG. 1;

FIG. 9 is an exploded view of an off-center section of the electrode pad referenced in FIG. 1;

FIG. 10 is a perspective view of the electrode pad referenced in FIG. 1 with the tab portions rotated upward; and,

FIG. 11 is a perspective view of the electrode pad referenced in FIG. 1 with the tab portions rotated downward.

The elements shown in broken lines are for illustrative purposes only and form no part of the claimed design.
